UNITED STATES PATENT OFFICE.

DARWIN HANAUER, OF LA GRANGE, ILLINOIS, ASSIGNOR TO KINNEY ROME COMPANY, A CORPORATION OF ILLINOIS.

MACHINE FOR TYING KNOTS IN SPIRAL SPRINGS.

Application filed September 18, 1926. Serial No. 136,282.

The free end of the wire at the large end of a spiral spring such as used in spring cushions and bed springs is knotted or tied about the wire forming the upper coil or turn of the spring; this operation being performed in a machine having a table on which the spring is set and an anvil adapted to be positioned between the free wire end and the turn or coil about which the knot is to be made. 10 The operator must take pains to position the spring in the machine and must use both hands to hold the spring in place while the knot is being made, in present types of machines. Because the operator is compelled to press forcibly on the lowermost wire of the spring while the knot is being made, his hands soon become calloused and sore. 15

Generally speaking, the object of the present invention is to improve the construction 20 of machines of the character described so as to increase their output and the accuracy of the work done thereby.

The object of the present invention, viewed 25 in one of its aspects, is so to construct a machine of the character described that it will be much easier for the operator to position springs on the same, using only one hand for the purpose.

A further object of the present invention is 30 to produce a simple and novel attachment for the machine which will automatically clamp the spring to the supporting table and make it unnecessary for the operator to employ either of his hands to hold the spring in place while the knot is being tied.

Machines of the type under consideration 35 are provided with a rocking work-supporting table that advances to receive the work and carries the latter rearwardly into operative 40 relation to the tying mechanism. I utilize these movements of the table to operate a clamp for holding the coil or turn of the spring that rests on the table, and for shifting an anvil from an idle position to a working 45 position. By retracting the anvil, it is removed from the path of a spring being set in place on the table and therefore the springs may be more quickly set in place than in the ordinary machine.

50 The various features of novelty whereby my invention is characterized will herein-after be pointed out with particularity in the claims; but, for a full understanding of my invention and of its objects and advantages, reference may be had to the following de-

tailed description taken in connection with the accompanying drawings, wherein:

Figure 1 is a top plan view of a machine equipped in accordance with the present invention; Figs. 2 and 3 are side views of the machine showing the table in its two different extreme positions, together with a spring resting on the table; Figs. 4 and 5 are similar vertical sections through the table, adjacent to the movable anvil, showing the anvil in two 60 different positions; and Figs. 6 and 7 are top plan views of the parts shown in Figs. 4 and 5.

Referring to the drawings, 1 represents a suitable base on which is supported a suitable 70 frame structure 2. 3 is a work supporting table fixed to the upper end of a swinging rocker 4; the rocker being supported on a horizontal transverse pivot 5. The rocker has an arm 6 extending rearwardly from the upper end thereof, and on this arm is a cam roller 7 lying within a cam groove 80 on a segmental gear 90 that is fixed to a transverse driving shaft 100. The parts heretofore described, together with the knot-tying means, 75 which will not be described in detail, are all 80 old and well known.

In the ordinary machine, when the free end of the wire at the large end of a spring is to be knotted, the spring, which is indicated at 85 A in the drawings, is laid on the table face down, with the free end of the wire lying behind an anvil and the adjacent portion of the upper coil of the spring lying in a groove in the anvil. This makes it necessary carefully 90 to insert the spring, an operation requiring careful attention by the workman and thus slowing down production. In accordance 95 with my invention I make that portion of the anvil that lies in rear of the groove movable, so that it may be shifted out of the way while the spring is being set in place and then be returned into its working position. This feature is best shown in Figs. 4 to 7. Referring 100 to these figures, the forward stationary part of the anvil is indicated at 8. The groove or seat 9 for the last complete coil of the spring is at the extreme rear end of this anvil. In rear of the member 8 is a vertical movable 105 plunger 10 slidably fitted in a socket 11 in the table. The plunger 10 has a rod 12 extending downwardly therefrom, the rod being provided at its lower end with a roller 13, and at a point above the roller with a collar 14. A compression spring 15 is placed between the 110

collar 14 and the underside of the table. On a stationary part of the machine, as best shown in Figs. 2 and 3, is an approximately horizontal shelf 16 on which the roller 13 runs. The parts are so proportioned that when the table is in its forward position, as shown in Fig. 2, the shelf 16 permits the spring 15 to force the plunger 10 down into the position shown in Figs. 4 and 6, thus permitting the spring to be set in the groove 9 in the stationary anvil without any interference on the part of the plunger 10. Then, when the table is drawn toward the rear, as shown in Fig. 3, the roller 13 rides rearwardly on the shelf or platform 16, forcing the rod or stem 12 and the plunger up into the position shown in Figs. 5 and 7, namely into the space between the free end of the wire of the spring A and the adjacent portion of the last turn or coil of this spring.

The second feature of my invention has to do with means for automatically clamping the spring on the table. To this end, I have pivoted to the front end of the table, at one side, a dog 18 whose nose 19 is adapted to swing between a position overlying the table, as shown in Fig. 3 and a position raised from the table as shown in Fig. 2. The dog has an extension 20 below its pivot point, and in this extension is an elongated slot 21. A stationary bar 22 extends forward from the frame work of the machine and is provided with a pin 23 that extends through the slot 21. A guide rod 24 is pivotally connected at its front end to the dog 18, above its pivot point, and extends rearwardly through a stationary guide 25. A small coiled spring 26 is attached at one end to the pivot pin 27 for the dog 18, passes in front of and underneath the stationary pin 23, and has its other end fastened to the extension 20 of the dog at a point 28 considerably in rear of the pin 23. This spring tends constantly to swing the clamping dog into locking position.

Consequently, as the table is rocked into its forward position as shown in Fig. 2, the nose of the dog is swung up. The movable anvil 10 is at this time withdrawn below the top of the table and therefore the spring to be operated upon may readily be set on the table, or the one that has been operated on may readily be removed. When a spring is set on the table and the machine set in operation so as to cause the table to rock toward the rear, the clamping dog is swung in the counterclockwise direction so that its nose will clamp down on the undermost coil of the spring on the table and thus firmly hold the spring in place. While the spring is being clamped in place, the movable anvil or plunger 10 rises, so that when the table is in its retracted position, the spring is being held in proper relation to the tying mechanism, so that the tie will be made without further effort on the part of the workman.

In Fig. 6 the parts are shown in the positions occupied by them when the table is forward, and just after a spring has been placed on the table. In Fig. 7 the table is assumed to be in its retracted position, the knot or tie ⁷⁰ a having just been completed.

It will thus be seen that a spring may be placed in the machine much more quickly and easily than hereinbefore and, for this reason, and for the further reason that the ⁷⁵ springs are automatically clamped on the supporting table, the output of a machine equipped in accordance with my invention will be greatly increased over that of the ordinary machine.

While I have illustrated and described with particularity only a single preferred form of my invention, I do not desire to be limited to the exact structural details thus illustrated and described; but intend to cover all forms and arrangements which come within the ⁸⁵ definitions of my invention constituting the appended claims.

I claim:

1. In a machine of the character described, a movable work-supporting table, an anvil mounted on the table for movements between a position in which it projects above the table and a position in which it is retracted below the table, and means controlled by movements of the table to shift the anvil from one of its positions to the other. ⁹⁰

2. In a machine of the character described, a rocking table, an anvil extending through the table, and means for moving the anvil between a position in which it projects above the table and a retracted position as the table rocks. ¹⁰⁰

3. In a machine of the character described, a rocking table, an anvil projecting through the table and having a stem extending downwardly therefrom, a spring tending to force the anvil down, and a stationary member in position to engage said stem and force the anvil up when the table is rocked in one direction. ¹⁰⁵

4. In a machine of the character described, a rocking table, two anvil members arranged on said table one in front of the other and spaced apart a short distance from each other, the rear anvil member extending through the table, and means for moving the latter anvil member between a position in which it projects above the table and a retracted position as the table rocks. ¹¹⁵

5. In a machine of the character described, a work supporting table movable between a receiving position and a work treating position, knot-tying means associated with said table, a clamp on said table remote from said knot-tying means, and means for automatically opening the clamp as the table approaches its receiving position and closing the clamp as the table moves toward its work treating position. ¹²⁵

6. In a machine for tying a knot in a coiled spring, a table mounted to rock forward and back, said table being larger than the end of a spring in which a knot is to be tied, knot-tying means associated with the table, a clamp mounted on the table at a point remote from the knot-tying means for engagement with the lowermost turn of a spring resting on the table, and means for automatically closing 10 the clamp as the table starts to rock toward the back and automatically opening the clamp when the table rocks forward.

7. In a machine for tying a knot in a coiled spring, a work supporting table movable between a receiving position and a work treating position, an anvil member mounted on the

table in position to lie between the free end of a spring resting on the table and the wire of the coil to which the free end is to be knotted, said anvil member being movable 20 between its working position and an idle position below the table, a clamp on the table at a point remote from said anvil member, and means for automatically closing the clamp on the bottom wire of a spring resting on the 25 table and moving said anvil member from its idle position to its working position as the table rocks from its receiving position to its work treating position.

In testimony whereof, I sign this specification. 30

DARWIN HANAUER.
